YARN CONDITIONING PROCESS

Joseph B. Dickey, Rochester, N. Y., assignor to
Eastman Kodak Company, Rochester, N. Y., a
corporation of New Jersey

No Drawing. Application December 21, 1938,
Serial No. 247,098

14 Claims.

(Cl. 28—1)

This invention relates to the conditioning of textile yarns and more particularly to the conditioning of filaments and yarns composed of organic derivatives of cellulose such as cellulose acetate, cellulose propionate, cellulose acetate propionate, and cellulose acetate butyrate, to render them more amenable to textile operations such as knitting and the like.

As is well known in the manufacture of yarns, particularly those composed of or containing cellulose organic derivatives, it is necessary to treat the yarn in order to reduce the tendency toward breakage of the individual filaments or fibers when they are subjected to various mechanical strains and to lubricate the yarn in order to facilitate handling in such operations as spinning, twisting, winding and reeling. It is also necessary to treat yarn to adapt it for use as warp or filling or for the manufacture of various types of knitted fabrics. In knitting, it is particularly important that the yarn be soft and pliable in order that it may conform readily to the contour of the needles and thus produce a closely knit fabric free from such defects as "stitch distortion," "pin holes," "laddering," and the like.

Heretofore it has been proposed to employ softening agents such as polyhydric alcohols and similar agents as ingredients of yarn conditioning or lubricating formulas, generally in connection with mineral, animal or vegetable oils. It has been found, however, that most of the known softening agents and the various formulas containing them have certain drawbacks, one of the most serious of which is high vapor pressure, and in some cases too drastic a solvent action on the yarn. Many of such agents possess slight or insufficient solvent power for the lubricants with which they are used, and it is accordingly necessary to employ blending agents or emulsifying agents in order to obtain operable yarn treating formulas. In addition, many of the known softening and lubricating agents are insufficiently soluble in water to permit satisfactory removal by aqueous scour baths.

This invention has as its principal object to provide an entirely new class of yarn conditioning agents which are particularly adapted for the treatment of yarns composed of or containing organic derivatives of cellulose and capable of lubricating, softening and rendering such yarns more amenable to knitting and other textile operations. A further and specific object is to provide a class of conditioning agents which augment or assist the lubricating action of various lubricants when applied to such yarns. A still

further object is to provide yarn softening and lubricating formulas which can be readily removed from the yarns by the usual scour baths. A still further object is to provide an improved method for the conditioning of yarns, particularly those composed of or containing organic derivatives of cellulose such as cellulose acetate, whereby the yarn is rendered soft and pliable and capable of employment in a variety of textile operations where complicated designs or stitches are employed. Another object is to provide an improved type of yarn which is especially amenable to textile operation including circular knitting, weaving, spinning and the like. Other objects will appear hereinafter.

These objects are accomplished by the following invention which, in its broader aspects, comprises the discovery that phosphated polyhydroxy alkoxyalkyl ethers and alkyl and aryl ethers of mono- and poly-functional alcohols having the following general formula:

(A) $(CH_2)_n-O-R-O-(CH_2)_n-Y$

where Y is a phosphoric acid ester derivative, said ester being derived from the group of compounds consisting of the free acid, its esters, and organic and inorganic salts, R is an alkyl group, R¹, R² and R³ are organic radicals selected from the group consisting of the substituted and unsubstituted alkyl, aryl or heterocyclic groups, L is a mono-valent substituent selected from the group consisting of hydrogen, hydroxy, acetal, ether, etc., and n is 0, 1, 2, etc., and b is 0, 1, 2, etc., 50 may be used as yarn conditioning agents and particularly as softening agents, with or without the addition of animal, mineral, or vegetable oils in the treatment of yarns composed of or containing organic derivatives of cellulose. I have 55

found that these compounds when employed as described in the detailed examples set forth below have a slight solvent and/or softening action on cellulose organic derivative yarns which renders such yarns soft and pliable without at the same time having too drastic an action thereon.

Examples of the preparation of typical compounds of this type are as follows:

PREPARATION OF COMPOUNDS

10

Example 1

28.6 gm. of β -hydroxyethyl cetyl ether are dissolved in chloroform and treated with 16 gm. of phosphorus oxychloride in the cold and the reaction is completed by warming. The chloride is hydrolyzed with aqueous sodium bicarbonate and the compound obtained by concentrating the liquors. The disodium β -hydroxyethyl cetyl ether phosphate is water soluble. The product of reaction has the formula:

25

One mole of

is reacted in a mixture of dioxane and pyridine with one mole of $(\text{C}_{16}\text{H}_{33}\text{O})_2-\text{PO}-\text{Cl}$.

30

Example 3

One mole of

35

is reacted as previously described with two moles of phosphorus oxychloride and the potassium salt prepared.

Example 4

One equivalent of oleyl $-(\text{OC}_2\text{H}_4)_n-\text{OH}$ is treated in a chloroform pyridine mixture with one equivalent of

and the product worked up as described in Example 1 so as to obtain a mono-potassium salt. The reaction product has the formula:

60

Example 5

25.2 gm. of $\text{HO}-\text{C}_2\text{H}_4-\text{OC}_{10}\text{H}_{20}-\text{OC}_2\text{H}_4\text{OH}$ are heated with 25 gm. of phosphoric acid at 110-140° under reduced pressure for twenty hours. The phosphate thus obtained may be treated, if desired, with bases such as sodium, potassium or ammonium hydroxide, tetramethylammonium hydroxide, etc., triethylamine, triethanolamine, dimethylcyclohexylamine, morpholine, ditetrahydrofurfurylamine, etc. to prepare mono or di-basic salts. The reaction product has the formula:

Example 6

31.4 gm. of glyceryl mono-cetyl ether are dissolved in pyridine and treated with one equivalent of

and the reaction is completed by warming. The pyridine is removed under reduced pressure and the chloride is hydrolyzed. Any desired basic salt may be prepared. If desired, two phosphate groups may be introduced. The reaction product has the formula:

Example 7

20

are treated in chloroform with 50 gm. of

and the reaction is carried out and worked up as previously described. The tetramethyl ammonium hydroxide or benzyl trimethyl ammonium hydroxide salt is prepared. The reaction product has the formula:

Example 8

45

One equivalent of

is reacted with two equivalents of phosphorus oxychloride in pyridine and the morpholine salt is prepared.

Example 9

55

One equivalent of

is dissolved in pyridine and treated with one or more equivalents of

and the product worked up to give an ethanolamine salt.

Example 10

70

28.8 gm. of

Example 18

A conditioning liquid particularly useful in the preparation of cut staple fibers made of cellulose acetate and which may be used for other textile operations is made up as follows:

	Parts
Water soluble cellulose ether	1
$\text{CH}_3-\text{O}-\text{P}(\text{O}(\text{Na}))_2\text{S}-\text{ONa}$	
10	
CH ₃ -O Naphthetyl	1-10
Olive oil	98-99

Other examples of yarn conditioning compositions which may be applied to various types of yarns, particularly those composed of or containing cellulose acetate, cellulose acetate propionate, cellulose acetate butyrate, and similar cellulose organic acid esters in accordance with my invention and which render such yarns soft and pliable and especially well adapted for various textile operations, particularly knitting, are as follows:

Example 19

25	Blown olive oil..... Oleyl (OC_2H_4) _{1, 2} , etc., $-O P(=S)(OCH_3)-ONa$	Parts 60-60
	Tetrahydrofurfuryl lactate.....	1-10 30

Example 20

30	HOC ₂ H ₄ O C ₁₀ H ₂₀ -O-C ₂ H ₄ -O-P(=O)(OH) ₂	Cyclohexylamine salt.	2-5
	Neat's-foot oil.....	Cyclohexylamine salt	98-95

Example 21

	<chem>CC1(C)C(OCC2CCCCC2)C(OCC3CCCCC3)C(OCC4CCCCC4)C1</chem>	
40	<chem>CC1(C)C(OCC2CCCCC2)C(OCC3CCCCC3)C(OCC4CCCCC4)C1</chem>	1-20
45	<chem>CC1(C)C(OCC2CCCCC2)C(OCC3CCCCC3)C(OCC4CCCCC4)C1</chem>	Blown neat's-foot oil Ethanolamine propionate butyrate
		79-80 20-30

Example 22

O H Tetramethylammonium hydroxide salt

O H Tetramethylammonium hydroxide salt..... 1-10

55

$\begin{array}{c} \text{CH}_2-\text{O}-\text{P} \\ | \\ \text{O} \end{array}$

$\begin{array}{c} \text{O} \\ | \\ \text{CH}_2 \\ | \\ \text{O} \\ | \\ \text{CH}_2 \\ | \\ \text{CH}_2-\text{O}-\text{C}_6\text{H}_5 \end{array}$

60 Sperm oil.

99-90

Example 23

65	Pentaerythritol triethyl ether diammonium phosphate Blown sperm oil Sodium sulfate Oleic acid Diethylene glycol

Example 24

70	Teased oil.	34-2
	Castor oil.	35
	Di- β -methoxyethyl succinate.	36
	OH Triethanolamine	
	OH Triethanolamine	1-10
	(n is 1, 2, etc.)	

Example 25

Example 26

CH-O-Naphthenic		
	OC ₄ H ₉	
CH ₂ -O-P		
	S	
Mineral oil	OH-Diethyl cyclohexyl amine	1-10 99-90 20

Example 27

Water	75
Water soluble cellulose ester	5
Sulfonated castor oil	10
Mannitol dicetyl ether-dioleic ester tetrasodium-diphosphate.	10

Example 28

Fibers, threads, filaments, etc. composed of any textile material in general or cellulose acetate in particular can be lubricated for various textile operations such as weaving, knitting, spinning, preparation of staple yarns, etc. by applying thereto by means of a bath, wick, spray, etc. a suitable compound chosen from the group of compounds claims in this application, as for example:

and

Any of the above composition may be applied to the yarn intended for use in circular knitting by means of a bath, wick, spray, roller, pad or any suitable means. The amount of conditioning liquid applied may vary between 5-25% by weight of the yarn. Usually, however, the amount of conditioning liquid applied is about 10-15% by weight of the yarn. Yarn composed of cellulose acetate conditioned as described above gives excellent results when used in the circular knitting process.

As will be apparent from the above examples and description the conditioning agents of my invention may be applied by a wide variety of methods. For example, I may employ the agent as an ingredient of the spinning dope from which the filaments are formed, the amount of the agent so employed depending upon a number of factors, such as the particular cellulose derivative used in making the yarn, the solvent or solvent combination used in making up the spinning solution, and the degree of softness or pliability desired in the yarn, etc.

If the conditioning agent is to be applied to the yarn after spinning, this may be done by bringing the yarn in contact with a wick, roll, or felt wet therewith, or the liquid may be applied by immersion, spray, or otherwise. The particular point at which the liquid is applied may vary. It may, for example, be applied to the yarn in-

are dissolved in a mixture of chloroform and pyridine and treated with 16 gm. of thraquinone are finely ground in a suitable mill with one pound of

and the reaction is completed by warming. The reaction product has the formula:

15 Example 11

One equivalent of

is treated with one equivalent of phosphorus pentasulfide in an oil bath at 50-150° until the reaction is complete. The product is treated with water and neutralized with morpholine. The reaction product has the formula:

30 Example 12

One equivalent of the reaction product from tetrahydrofurfuryl alcohol and ethylene oxide is treated in boiling chloroform with phosphorus pentoxide. The reaction product is treated with water and ditetrahydrofurfurylamine. The reaction product has the formula:

40 Example 13

45 33.4 gm. of m-hydroxy cetyl phenyl ether are dissolved in a mixture of chloroform and pyridine and treated with 16 gm. of phosphorus oxychloride. The reaction product is worked up as previously described and any desired salt such as the triethylamine, benzyltrimethylammonium hydroxide, etc. prepared. The reaction product has the formula:

55 In a similar manner we may react:

65 Example 14

One mole of

70 is dissolved in a mixture of dioxane and pyridine and reacted with one mole of POCl_3 . The trimethylbenzylammonium hydroxide salt is prepared.

75 Example 15

2 pounds of 1-methylamine-4-ethylaminoan-

and poured into 200 gallons of water, then heated to 60-85°. 100 pounds of cellulose acetate in the form of taffeta, crepe fabrics, etc. are entered and dyed a deep blue shade. Soft water is not necessary with a dispersing agent of this type.

10 In accordance with the invention these compounds may be applied directly to the yarn during or after spinning, or may be added to the spinning solution itself. I have found that these compounds have exceptional solvent powers which enable them to dissolve mineral oils and blown and unblown, drying and semi-drying, vegetable and animal oils and accordingly they may be, and preferably are, employed as ingredients of yarn conditioning or lubricating formulas in conjunction with agents which function wholly or partially as lubricants.

15 In the following examples and description I have set forth several of the preferred embodiments of my invention, but they are included merely for purposes of illustration and not as a limitation thereof.

20 My invention will be more readily understood by reference to the following examples in which typical applications of the invention are set forth.

25 Example 16

30 Dimethylcyclohexylamine salt is applied to textile materials (silk, wool, cotton, viscose, cellulose acetate, etc.) by means of a bath, wick, spray, roller, etc., to facilitate their knitting, weaving, spinning etc. Yarns lubricated with the above type of lubricant are of special value in the preparation of cut staple fibers. These fibers may be oiled before or after cutting.

35 Example 17

40 A conditioning liquid is made up as follows:

	Parts by weight
Ditetrahydrofurfuryl ether	50
$\text{CH}_2-\text{OCH}_{16}\text{H}_{33}$	55
$\text{CH}-\text{O}-\text{C}_17\text{H}_{33}$	45
$\text{CH}_2-\text{O}-\text{P}(\text{H}_2)-\text{O}-\text{CH}_2-\text{OH}$	Diethyl cyclo hexylamine salt
$\text{CH}_2-\text{O}-\text{P}(\text{H}_2)-\text{O}-\text{CH}_2-\text{OH}$	Diethyl cyclo hexylamine salt
Water	60

45 and applied to textile materials such as silk, wool, viscose, cotton, cellulose acetate, etc., as in Example 16. If the yarn is intended primarily for knitting the amount of conditioning liquid applied may vary from 4-25% by weight of the yarn and if for weaving between 1-5% by weight. Cellulose acetate filaments treated as described are quite soft and pliable and give improved results in various textile operations such as weaving, knitting etc., and especially in the preparation of cut staple fibers.

50 Other examples of suitable lubricating mixtures having anti-static properties which are used as described in Examples 16 and 17 follow.

side or outside the spinning cabinet, between the guide and godet roll, between the godet or other roll or guide and the point of winding and/or twisting. In some cases, the liquid may even be applied to the yarn after winding onto cones, spools, bobbins, or the like or by the so-called "bobbin to bobbin" method. In the case of staple fiber manufacture, the liquid may be applied to the yarn prior to, or after cutting into staple lengths.

The amount of the agent so employed will vary widely depending upon the results desired, the specific nature of the material to which the agent is applied, the use to which the yarn is eventually to be put and other factors. For example, in a given case where a cellulose organic acid ester yarn such as a yarn composed of cellulose acetate, is intended for knitting, about 4 to 25% or more by weight, based on the weight of the dry yarn, may be satisfactory, while if the yarn is intended for weaving, the amount may vary between about 1 and 5%.

Although in the above examples I have referred primarily to yarn treating compositions containing only the conditioning agent and an oil, other ingredients such as solvents, non-solvents, emulsifying agents, blending agents and the like, may be added within the scope of my invention. Likewise, various dyes or other coloring matter may be included in case it is desired to permanently or fugitively tint or dye the material undergoing treatment.

Although I have found it convenient to illustrate my invention by reference to compositions containing specific percentages of the various ingredients, these percentages may vary widely depending upon the particular purpose for which the composition is intended. For example, if it is desired to control the solvent or softening action of the conditioning agent the amount of the agent may be adjusted as, for example, by reducing the amount of the agent and correspondingly increasing the amount of oil or other ingredient.

While I have described my invention with particular reference to the treatment of yarns composed of organic derivatives of cellulose such as cellulose acetate, the conditioning agents and formulas described herein are applicable to the conditioning of many other types of cellulose derivative yarns such as those composed of or containing cellulose propionate, cellulose butyrate, cellulose acetate propionate, cellulose acetate butyrate, ethyl cellulose, methyl cellulose, benzyl cellulose and others, as well as to the conditioning of silk, wool, cotton, viscose and other natural or artificial materials.

The term "yarn" as used herein and in the claims is to be understood as including a single filament, a plurality of filaments associated into the form of a thread, either of high or low twist, single or multiple threads associated or twisted together, composite threads composed of a mixture of natural and artificial filaments or a composite thread formed by twisting together individual strands of natural or artificial materials, as well as cut staple fibers produced from natural and/or artificial filaments or threads and spun yarn produced from such staple fibers.

As indicated above, the yarn conditioning agents of my invention are exceptionally good solvents for a wide variety of mineral, blown and unblown, drying and semi-drying animal and vegetable oils such as cottonseed, olive, castor, neat's-foot, sperm and other oils. This en-

ables them to be used with any of such oils in making up a variety of yarn treating formulas of varying composition.

The yarn conditioning method and compositions of my invention possess many outstanding advantages. The fundamental and outstanding characteristic of the agents employed in accordance with the invention is their ability to soften yarns, especially those composed of or containing organic derivatives of cellulose such as cellulose acetate and render them soft and pliable and amenable to various textile operations, especially operations such as those involved in weaving and knitting where complicated designs or stitches are employed, without too drastic an action on the yarn material. Another outstanding characteristic of these compounds is their exceptional solvent power for a wide variety of mineral, animal, and vegetable oils and their ability to act as lubricating assistants in conjunction with these oils when applied to such yarns. In addition, due to their solubility in water, they may be readily removed from yarns and fabrics by means of the usual aqueous scour baths. By employing the yarn conditioning agents and method of my invention as herein described, one is enabled to obtain highly satisfactory results in the manufacture of yarns and woven fabrics and especially the production from these yarns of closely knit fabrics free from defects such as pin holes, stitch distortion, ladderizing and the like.

What I claim is:

1. The process of conditioning yarn to render it more amenable to textile operations including knitting, weaving, spinning and the like, which comprises applying thereto a lubricating and softening composition containing as its essential lubricating and softening component an ether selected from the group consisting of the phosphated polyhydroxy alkoxyalkyl ethers, and alkyl and aryl ethers of mono- and poly-functional alcohols.

2. The process of conditioning yarn composed of or containing organic derivatives of cellulose to render it more amenable to textile operations including knitting, weaving, spinning and the like, which comprises applying thereto a lubricating and softening composition containing as its essential lubricating and softening component an ether selected from the group consisting of the phosphated polyhydroxy alkoxyalkyl ethers, and alkyl and aryl ethers of mono- and poly-functional alcohols.

3. The process of conditioning yarn composed of or containing cellulose acetate to render it more amenable to textile operations including knitting, weaving, spinning, and the like, which comprises applying thereto a lubricating and softening composition containing as its essential lubricating and softening component an ether selected from the group consisting of the phosphated polyhydroxy alkoxyalkyl ethers, and alkyl and aryl ethers of mono- and poly-functional alcohols.

4. The process of conditioning yarn composed of or containing cellulose acetate to render it more amenable to textile operations including knitting, weaving, spinning, and the like, which comprises applying thereto a lubricating and softening composition containing as its essential lubricating and softening component an ether selected from the group consisting of the phosphated poly-hydroxy alkoxyalkyl ethers, and alkyl and aryl ethers of mono- and poly-functional alcohols, and a textile lubricant.

5. The process of conditioning yarn composed of or containing cellulose acetate to render it more amenable to textile operations including knitting, weaving, spinning, and the like, which 5 comprises applying thereto a lubricating and softening composition containing as its essential lubricating and softening component glycerol dioleyl ether-phosphate diethyl cyclohexylamine salt.
- 10 6. The process of conditioning yarn composed of or containing cellulose acetate to render it more amenable to textile operations including knitting, weaving, spinning, and the like, which 10 comprises applying thereto a lubricating and softening composition containing as its essential lubricating and softening component disodium thio-phosphate of ethylene glycol naphthyl ether.
- 15 7. The process of conditioning yarn composed 15 of or containing cellulose acetate to render it more amenable to textile operations including knitting, weaving, spinning, and the like, which comprises applying thereto a lubricating and softening composition containing as its essential lubricating and softening component pentaerythritol triethyl ether phosphate diammonium salt.
- 20 8. A conditioning agent for rendering textile 20 yarns composed of or containing organic derivatives of cellulose more amenable to textile operations including knitting, weaving, spinning, and the like, which comprises an ether selected from the group consisting of the phosphated polyhydroxy alkoxyalkyl ethers, and alkyl and aryl ethers of mono- and poly-functional alcohols, and a textile lubricant.
- 25 9. Textile yarns amenable to textile operations 25 including knitting, weaving, spinning, and the like, impregnated with a lubricant containing as 30 its essential lubricating and softening component an ether selected from the group consisting of the phosphated polyhydroxy alkoxyalkyl ethers, and alkyl and aryl ethers of mono- and poly-functional alcohols.
- 30 10. Textile yarns composed of or containing 30 organic derivatives of cellulose amenable to textile operations including knitting, weaving, spinning, and the like impregnated with a conditioning agent comprising an ether selected from the group consisting of the phosphated polyhydroxy alkoxyalkyl ethers, and alkyl and aryl ethers of mono- and poly-functional alcohols.
- 35 11. Textile yarns composed of or containing 35 organic derivatives of cellulose amenable to textile operations including knitting, weaving, spinning, and the like, impregnated with a conditioning agent comprising an ether selected from the group consisting of the phosphated polyhydroxy alkoxyalkyl ethers, and alkyl and aryl ethers of mono- and poly-functional alcohols, and a textile lubricant.
- 40 12. Textile yarns composed of or containing 40 cellulose acetate amenable to textile operations including knitting, weaving, spinning, and the like, impregnated with a lubricant comprising glycerol dioleyl ether-phosphate diethyl cyclohexylamine salt.
13. Textile yarns composed of or containing 45 cellulose acetate amenable to textile operations including knitting, weaving, spinning, and the like, impregnated with a lubricant comprising disodium thio-phosphate of ethylene glycol naphthyl ether.
14. Textile yarns composed of or containing 50 cellulose acetate amenable to textile operations including knitting, weaving, spinning, and the like, impregnated with a lubricant comprising pentaerythritol triethyl ether phosphate diammonium salt.

JOSEPH B. DICKEY. 40
